UNITED STATES PATENT OFFICE.

WILLIAM EDWARD GRANT AND MONTAGUE BUTLER BEAN, OF SYDNEY, NEW SOUTH WALES, AUSTRALIA.

SOCKET FOR ELECTRIC-LIGHT GLOBES.

Application filed March 12, 1925, Serial No. 15,027, and in Australia November 20, 1924.

This invention relates to electric lamp sockets or holders for bayonet type lamps but more particularly refers to a type of socket in which the lamp is forced against and held 5 up to fixed contacts to which the conducting wires are led.

The object of the invention is to provide an improved socket or holder which having few parts shall eliminate the usual small plungers, springs and screws, and therefore permit 10 of economical construction and very rapid and easy wiring and which shall ensure absolute contact under all conditions of vibration and which shall allow of easy and cheap renewal of parts. Further features of the invention are an efficient cord grip and a shade 15 holder which permits easy removal and replacement of the shade. Still another feature of the invention is a simple lamp lock 20 which, while not rendering it impossible for anyone acquainted with the construction of the device to extract the lamp, would prevent theft in most ordinary cases.

Accordingly therefore the invention consists of a shouldered divided plug of an insulating material, fixed contacts in said plug, 25 an enveloping sleeve, an outer casing, a shade retaining means and a lamp locking device, all of which parts together with their assembling will now be described with reference to the accompanying drawings in which:—

Figure 1 is a perspective view of the outer casing showing the shade retaining means and the lamp lock,

Figure 2 is a perspective view of the inner sleeve,

Figure 3 is a perspective view of the inner contact retaining plug,

Figure 4 is a perspective view of the plug 40 showing its two parts,

Figure 5 is a perspective view of the shade retaining and lamp locking ring,

Figure 6 is a sectional elevation of the plug shown in Figure 3 on a section exposing a 45 contact,

Figure 7 is a sectional elevation of the complete holder showing the relation between the various parts, and

Figure 8 is a sectional elevation on a plane 50 at right angles to that of Figure 7 of the complete holder with one part of the inner plug removed.

The inner plug is formed in two approximately equal portions 9 and 10 which are substantially of the shape shown in Figure 4, the

part 9 having a central longitudinal groove 11 and a pair of grooves 12 while the other part 10 has a central longitudinal projecting key 13 which corresponds with and fits into the groove 11 when the portions are placed together. The part 10 has also a pair of parallel grooves 14 one on each side of the key 13 which correspond with grooves 12 in part 9.

The part 10 has a pair of contacts 15 keyed into it as shown in Figure 6 and situated at 65 the end of grooves 14. These contacts have downwardly projecting points 16 which enter the corresponding depressions 17 in the portion 9. The grooves 14 have also waves 18 which occur opposite corresponding depressions 19 in the grooves 11 of portion 9 which is secured to portion 10 by the screw 20 as shown in Figures 3 and 6. The lower ends of the plug formed by these two parts is shouldered as shown at 21 and a pair of diametrically opposed projections 22 formed thereon. 70

The complete plug fits into a sleeve 23 which is provided with an opposing pair of slots 24 corresponding to the projections 22, an outwardly extending flange 25 at its lower 80 end and an inwardly extending flange 26 at its upper end.

The sleeve 23 in turn fits into the outer casing 27 the inner surface of which is cylindrical while the outer surface is threaded. At 85 the bottom of this casing are formed two grooves 28 which are diametrically opposed and which commence with a short vertical length and then run circumferentially, rising gradually as they progress, thus forming an 90 inclined guideway.

In operation the ends of the incoming conducting wires 29 which have been led through the outer casing 27 of the sleeve 23 are bared and the wires are then placed one in each of the grooves 12 so that the bared ends 30 lie in the depressions 17. The other portion 10 of the plug is then placed in position so that the contact pieces 15 bear against the ends 30 as shown in Figure 6 and the parts 9 and 10 are 95 clamped together by the screw 20 so that the wires 30 are in good electrical contact with the pieces 15, and are gripped along the length of the channel formed by the grooves 12 and 14, additional security being obtained 100 by the action of the waves 18 and depressions 19. The key 13 as well as being a centering means increases the insulation between the wires 29 and prevent stray ends of flexible wire coming into contact. 105

The complete plug is then inserted in the sleeve 23 so that the projections 22 enter the slots 24, a coil spring 31 being first placed round the plug so that it bears against the shoulder 21 and the upper flange 26 as shown in Figures 7 and 8. The plug and sleeve together are then slipped into the outer casing 27 so that the flange 25 bears against the lower edge of the casing 27 and the plug projects 10 through the neck 32 at the top. The holder is then ready to receive the lamp of which the base 33 and pins 34 are shown in Figures 7 and 8.

In placing the lamp in position the pins 34 15 are entered in the lower ends of the slots 24 and the lamp together with the sleeve and plug are turned until the pins come opposite to the entrance of the groove 28. The lamp is then pushed in and turned so that the pins 20 ride up the inside of the grooves 28 until the contacts on the base of the lamp are forced hard against the contacts 15. And these opposing contacts are kept in exact registration by reason of the fact that the pins 34 and 25 projections 22 both pass through the slots 24 so that as the lamp is turned the plug turns at the same rate, the contacts 15 being arranged in the correct position in the first place.

For the shade holder there are two rings 30 35 and 36, the upper of which is threaded and screws upon the external threads on the casing 27, the lower 36 has a plain interior in which two opposing gaps 37 are formed so arranged that the ring may be passed over the 35 projecting grooves 28 and when partially rotated the parts 38 rest upon these grooves thus forming a support for the shade. The upper ring is screwed down to clamp it in position.

The lamp lock device, the fitting of which is 40 optional, consists of a slot 39 formed in one or both of the grooves near its entrance and a pin or pins 40 projecting downwards from the ring 36 and so arranged that it will enter the slot or slots 39 and form a stop past which 45 the pin 34 of the lamp will not pass. To remove the lamp when the shade is secured in position it is necessary to screw the ring 35 up, thus lifting the shade and lift the ring 36, thus withdrawing the pin 40 to allow the lamp pin 34 50 a clear passage. This operation would do much to prevent theft of lamps but would not make it impossible.

In Figure 7 the position of the shape 41 relative to the other parts is indicated by dotted lines. It is illustrated with the ring 36 55 lifted clear of the grooves 28 so that the lamp 33 the pins of which have just entered the vertical parts of grooves 28, may be turned into its final position. Figure 8 also illustrates this stage in the fitting of the lamp.

In order to make the wiring and the assembling of the device easier, holes 42 may be drilled through the projecting points 16. The bared ends 19 of the wire may then be threaded through and the extreme ends bent upwards 65 round the points of 16. When it is desired to use the holder in a situation where it is necessary to attach it directly to some rigid support, a thread either internal or external may be formed on the neck 32 by means of which 70 the casing 27 is attached to a flange or plate on the bottom or support or alternatively the casing may be provided with a flange and be connected direct to the ceiling or wall or batten. In either case the plug is shortened so as 75 not to project beyond 32, it not being necessary to have a cord grip sufficient to take the weight of the whole arrangement.

The outer casing and inner sleeve are preferably formed in stamped metal, while the 80 plug is constructed of suitable moulded insulating material with metal contact pieces.

We claim:—

1. In an electric lamp holder of the type in which an outer casing has outwardly extending impressed grooves to receive the lamp pins a shade retaining means comprising a thread on the exterior of said casing, a threaded ring and a removable ring having a pair of opposing recesses in its inner edges. 85

2. In an electric lamp holder of the type in which an outer casing has outwardly extending impressed grooves having stop-pin receiving slots to retain the lamp pins, a lamp locking device comprising a thread on the exterior of said casing, a threaded ring, a removable ring, and a downwardly projecting pin or pins on said removable ring. 95

3. In a lamp socket a diametrically divided plug having wire receiving grooves therein 100 provided with depressions, contact members anchored in one part of the plug, and projections on the contact members adapted to enter said depressions to clamp and electrically contact with the terminals of wires located in 105 said grooves.

4. A lamp socket as claimed in claim 3 characterized by the provision of a longitudinal key on one of the plug parts and a corresponding key way in the other plug part. 110

5. A lamp socket as claimed in claim 3 characterized in that the parts of the plug are provided with corresponding depressions and projections in the walls of the grooves for crimping the wires to prevent withdrawal 115 thereof.

In testimony whereof we have affixed our signatures.

WILLIAM EDWARD GRANT.
MONTAGUE BUTLER BEAN.
